UNITED STATES PATENT OFFICE.

FRANK M. STEINER AND WALTER S. GRAVES, OF MINNEAPOLIS, MINNESOTA, AS-SIGNORS, BY MESNE ASSIGNMENTS, TO STEINER SALES COMPANY, OF SALT LAKE CITY, UTAH, A CORPORATION OF UTAH.

TOWEL CABINET.

Application filed July 15, 1921. Serial No. 484,841.

The object of our invention is to provide means in connection with a towel cabinet which will allow only a certain length of the clean toweling to be withdrawn by the user, the length of the towel so withdrawn being previously ascertained or determined when the device is set up and thereby a roll of toweling is made to last for a much longer time than under usual conditions of delivery and use.

The invention consists generally in various constructions and combinations, all as hereinafter described and particularly pointed out in the claims.

15 In the accompanying drawings forming part of this specification,

Figure 1 is a front view of a towel cabinet embodying our invention, on the section line 1—1 of Figure 2,

20 Figure 2 is a vertical sectional view, showing the position of the roll of toweling in the cabinet and the manner of using it,

Figure 3 is a detail sectional view, showing the operation of the clamping device,

25 Figure 4 is a sectional view on the line 4—4 of Figure 1,

In the drawing, 2 represents the cabinet, made preferably of sheet metal, though any other suitable material may be used, having a chamber 3 in which the roll of clean toweling 4 is placed. A rear wall 5 is provided for the cabinet, which may extend, as shown in Figure 3, down below the floor or bottom wall 6, and form a back plate extending from the cabinet to the floor of the room where it is placed.

30 7 is a door hinged at 8 and having a suitable fastening means 9. This door, when opened, allows the roll to be conveniently placed in the chamber. A partition or wall 10 extends upwardly from the floor 6 and has a rounded upper edge 11 over which the loose end of the towel is carried. An opening 12 is formed in the bottom of the cabinet 40 in the rear of the partition 10 and through this opening the toweling is fed down to the user.

We prefer to provide a tension plate 13 within the chamber 3, pivoted at 14 and held 45 yieldingly toward the partition 10 by the tension of a compression spring 15 that is mounted in a suitable way, such as on a pin 16. The friction of this plate on the toweling tends to retard its delivery and prevents

momentum being imparted to the roll, which would cause it to unwind more than the user would require or should have.

A plate 17 is provided below the opening 12, supported in brackets 18 and 18^a, the former being rigidly mounted on the rear wall of the cabinet and the latter having hinges 19 which allow the bracket 18^a to have a limited oscillating movement. Pins 20 and 20^a are provided fitting sockets in the ends of the plate 17 above the longitudinal center thereof, as shown in Figure 3, these pins forming horizontal pivots on which the plate 17 is free to oscillate and the pin 20 fits within a bayonet slot 21 in the bracket 18 and serves to normally hold the plate against outward swinging movement during the operation of unwinding the length of towel from the roll.

The upper portion of the plate 17 is preferably beveled at 22 and in the rear of this beveled portion a plate 23 is provided, having a flat surface between which and the plate 17 the surface of the clean towel is gripped and held. Normally, there is sufficient space in the rear of the plate 17 to allow the clean towel to be drawn down in a vertical direction and to limit the length of towel so withdrawn, we prefer to provide a receptacle 24 a suitable distance from the measuring plate so that when the towel is 50 grasped by the user and pulled straight down, the arms of the person withdrawing the towel will strike the upper edge of the wall of the receptacle, as indicated by dotted lines in Figure 2, and thereby further movement of the towel will be checked, and should the user pull his hands outwardly, clear the receptacle 24 and continue the pulling operation, the plate 17 will swing on its axis and grip the towel between its beveled 55 surface and the plate 23 and thereby the toweling will be clamped securely and any further pulling by the user of the towel will only serve to grip or clamp it more securely.

As soon as the user ceases to pull on the toweling, the heavier lower portion of the plate 17 will cause it to return from the position shown in Figure 3 to the vertical position shown in Figure 4. This will release the toweling and a fresh supply may be obtained by pulling downwardly, as indicated in Figure 2.

We prefer to mount a mirror 25 on the

plate 17 for the convenience of the user of the cabinet, the weight of the mirror aiding in returning the plate to its normal vertical position and retaining it in such position 5 until it is tilted by an outward pull on the towel.

We claim as our invention:

1. A towel cabinet comprising a casing having a chamber therein for a roll of clean 10 toweling and an opening in its wall through which the loose end of the toweling is fed in a vertical position to be grasped by the user standing below said cabinet, a downward vertical pull unwinding the towel from 15 the roll, means in the path of the arms of the user for limiting such downward pull, and means for gripping and positively 20 checking the feed of the toweling when the free end is pulled outward in a horizontal direction to clear said downward movement limiting means.

2. A towel cabinet comprising a casing having a chamber adapted to contain a roll 25 of toweling and provided with an opening in its wall through which the loose end of the roll is downwardly fed in a vertical position by a person standing below and in front of 30 said cabinet, means beneath said casing for limiting the direct downward pull on the toweling, and a clamp device below said casing for gripping the towel and preventing downward feed thereof when it is pulled horizontally.

3. A towel cabinet comprising a casing 35 having a chamber adapted to contain a roll of toweling and provided with an opening in its wall through which the loose end of the roll is fed, means beneath said casing for limiting the direct downward pull on 40 the toweling, and a clamp device for gripping the towel and preventing feed thereof when it is pulled outwardly and downwardly, said clamp device comprising a plate 45 mounted below said cabinet and normally vertical and adapted to be tilted by outward pull on the toweling for gripping it and checking the feed.

4. A towel cabinet comprising a casing 50 having a chamber therein for a roll of toweling and provided with an opening through which the loose end of the towel is fed, an eccentrically pivoted plate below said cabinet having a gripping surface past which the free end of the towel slides when a downward pull is exerted thereon, said plate tilting and its gripping surface clamping the towel web against the casing when an outward pull is applied thereto.

5. A towel cabinet comprising a casing 60 having a chamber for a roll of toweling therein and provided with an opening through which the loose end of the toweling is fed, a clamping plate pivoted below the casing and near the back of the cabinet adapted to engage the towel and grip it

against the back of the cabinet when an outward pull is exerted on the towel.

6. A towel cabinet comprising a casing having a chamber therein for a roll of clean toweling and provided with a feed opening 70 through which the loose end of the toweling is delivered, a plate hinged at one end below said casing to allow convenient insertion of the toweling behind the same and also mounted to rock on a horizontal axis and having a gripping surface for engaging and clamping the towel below the roll and outside the casing when an outward pull is applied thereto, said plate allowing the towel to move freely when a direct pull is exerted 80 thereon.

7. A towel cabinet comprising a casing having a chamber therein for a roll of clean toweling, an upright partition in the rear of said chamber over which the loose toweling is fed, a plate pivotally mounted in said chamber and having a surface between which and said partition the towel passes, and a spring for normally holding said plate toward said partition with a yielding pressure. 90

8. A towel cabinet comprising a casing having a chamber therein adapted to receive a roll of clean toweling and provided with an opening through which the clean end of the toweling is fed downwardly, an open space being provided beneath said casing to allow access of the user to the towel, a soiled towel receptacle being provided below said open space in the path of the hands of the user for limiting a direct downward pull 100 on the towel, and a gripping means adjacent to said casing back for clamping the toweling and preventing feed thereof when the user exerts an outward horizontal pull thereon.

9. A towel cabinet comprising a casing having a chamber therein adapted to receive a roll of clean toweling and provided with an opening through which the clean end of the toweling is fed downwardly, an open space being provided beneath said casing to allow access of the user to the towel, a soiled towel receptacle being provided below said open space in the path of the hands of the user for limiting a direct downward pull 110 on the towel, and a gripping means adjacent to said casing back for clamping the toweling and preventing feed thereof when the user exerts an outward horizontal pull thereon, said gripping means comprising a pivoted plate having an upper inner surface for contact with the towel and a lower edge engaged by the towel for tilting said plate to its gripping position when said outward horizontal pull is exerted on the towel. 120

10. A towel cabinet comprising a casing having a chamber therein to receive a roll of clean toweling and an opening through which the loose end of the towel is fed, a direct downward pull on the toweling un- 130

winding it from its roll, a plate pivotally supported beneath said casing to hang vertically and parallel with the back of the casing and having an upper surface for clamping with the depending portion of the towel against the casing, said plate permitting free feed of the towel when a direct downward pull is exerted thereon, and the lower portion of said plate having a surface for engagement with the towel to tilt said plate to its gripping position and check feed of the towel when an outward horizontal pull is exerted thereon.

11. A towel cabinet comprising a casing having a chamber therein for a roll of clean toweling and an opening in its wall through

which the loose end of the toweling is fed in position to be grasped by the user, the downward pull unwinding the towel from the roll, a plate pivoted between its upper and lower edges near the back of the cabinet leaving a shallow opening between the plate and the back of the cabinet whereby when the lower portion of the towel is pulled toward the user, it will carry with it the lower edge of the plate and cause its upper edge to grip the towel between it and the back of the cabinet.

In witness whereof, we have hereunto set our hands this twentieth day of June 1921.

FRANK M. STEINER.
WALTER S. GRAVES.
